TYPE-WRITING MACHINE.

1,054,875.

Specification of Letters Patent.

Patented Mar. 4, 1913.

Application filed August 31, 1912. Serial No. 718,069.

To all whom it may concern:

Be it known that I, CHARLES E. SMITH, citizen of the United States, and resident of the borough of Brooklyn, city of New York, in the county of Kings and State of New York, have invented certain new and useful Improvements in Type-Writing Machines, of which the following is a specification.

10 My invention relates to typewriting machines, and more particularly to tabulating mechanism, and has for its main object the provision of comparatively simple and efficient tabulating mechanism in which the 15 column stops may be readily set for different characters of tabulating work.

Some further objects of the invention may be briefly and generally stated to be as follows:—(1st) To provide a construction 20 which is in the nature of an attachment which may be readily applied to existing forms of typewriting machines, and in which attachment there are self-contained tabulating mechanism and means for readily 25 setting and clearing the column stops. (2nd)

To provide improved mechanism including a rotative carrier operatively connected to be rotated by the travel of the carriage and having a series of column stops mounted 30 thereon for movement into and out of operative column determining positions. (3rd) To provide in conjunction with said mechanism means for moving the column stops into and out of operative positions. (4th)

35 To provide improved means by which the travel of the carriage is made available for clearing the column stops. (5th) To provide improved means for releasing the carriage when the stop clearing means is rendered effective or operative. (6th) To provide improved means for locking the clearing mechanism in its operative position.

(7th) To provide improved means for automatically releasing the locking means of 45 the clearing mechanism after the stops have been cleared. (8th) To provide means whereby the tabulating mechanism, or parts thereof, are made to serve as a carriage scale and pointer to indicate the position 50 of the carriage at any point in its travel.

(9th) To provide an improved column stop construction by which the column stops may be sprung into and out of position on the

stop carrier and by which the stops are held against accidental displacement in either the 55 operative or inoperative positions to which they may be moved on the carrier. (10th) To provide comparatively simple mechanism of the character specified and by arranging various features of the construction at the front of the machine and so constructing them that the parts are brought more directly under the control of the operator and a manipulation of the parts is 60 facilitated.

65 To the above and other ends which will hereinafter appear, my invention consists in the features of construction, arrangements of parts, and combinations of devices to be set forth in the following description and particularly pointed out in the appended claims.

70 In the accompanying drawings wherein like reference characters indicate corresponding parts in the various views, Figure 75 1 is a fragmentary side elevation, with parts in section and parts omitted, of one form of typewriting machine embodying my invention. Fig. 2 is a detail fragmentary front elevation with parts in section of the 80 rack by which the tabulator mechanism is connected with the carriage, together with the means for supporting the rack in place. Fig. 3 is an enlarged detail fragmentary side elevation of the tabulator mechanism and 85 some of the associated parts. Fig. 3^a is a fragmentary detail side view of a modified form of releasing device, the associated carrier being shown in section. Fig. 4 is a fragmentary front elevation of the same, a 90 portion of the mechanism being sectioned away. Fig. 5 is a detail fragmentary horizontal sectional view of the same, the section being taken on the line $x-x$ of Fig. 3 and looking in the direction of the arrow at 95 said line. Fig. 6 is a fragmentary side view, with parts in section, of the clearing mechanism and some of the associated parts, the clearing mechanism being shown locked in the operated position. Fig. 7 is a detail 100 fragmentary side view, with parts in section, of the stop setting means and some of the associated parts, the stop setting device being shown in the operated position. Fig. 8 is a detail side elevation of a portion of 105 the tabulator mechanism showing a denomina-

national stop projected to operative position and the carriage release device actuated to release the carriage.

I have shown my invention embodied in the present instance in a No. 10 Remington machine in which the invention may be readily employed without modifying the structural features of said machines as they now exist. It should be understood, however, that the invention may be embodied in various characters of writing machines and that some of the features may be employed without others.

In illustrating the invention I have shown only so much of the No. 10 Remington machine as may be necessary to arrive at an understanding of my invention in its embodiment therein.

The frame of the machine comprises a base 1, corner posts 2 and a top plate 3. A carriage, represented as a whole by the reference numeral 4, supports a rotative platen 5 and is supported by anti-friction balls or rollers 6 for movement from side to side of the machine over the top plate. The carriage is propelled by the usual spring drum 7 operatively connected to the carriage by a strap or band 8, the carriage being controlled in its step-by-step letter space movement by the usual escapement mechanism. Thus a feed rack 9 is supported on arms 10 pivoted at 11 to the carriage. One or more springs 12 coöperate with the arms 10 to press the feed rack into mesh with a feed pinion 13. The feed pinion is connected in the usual manner with a double escapement wheel 14, coöperative with a feed dog 15 to control the letter space movement of the carriage. The feed dog is carried by a dog rocker 16 pivoted at 17 to a bracket 18 which latter is fixedly secured to the frame of the machine. The dog rocker is controlled in the usual manner from the universal bar actuated at each depression of a printing key 18^a. Each key is connected through a key lever (not shown), links 19 and 20, and a sub-lever 21 with an upwardly and rearwardly striking type bar 22 which strikes against the front face of the platen. The usual carriage release key 23 forms a part of a lever 24 which is pivoted at 25 to an end bar of the carriage, the rear end of the lever extending beneath the feed rack 9 to lift it and thus disengage the rack from the feed pinion to free the carriage from control of its escapement mechanism. The lever 24 is slotted at 26 to receive a headed screw 27 received at its threaded end in a tapped opening in the carriage frame. The screw 27 guides the forward end of the lever 24 and limits the movement thereof. There may be one of these release keys and levers at each side of the carriage. A pointer 28 is fixed by a screw 29 to the forward fixed carriage rail and coöperates with a carriage

scale 30 carried by the forward cross bar of the carriage.

The parts thus far described are or may be of the usual construction embodied in the No. 10 Remington machine.

Forwardly extending bracket arms 31 are detachably secured to the carriage frame and extend forwardly therefrom and are bent downwardly at their forward end portions where they are tapped to receive shouldered thumb screws 32. These screws are adapted to be received in angular slots 33 in a rack 34.

From an inspection of Fig. 2 it will be observed that when the rack is in the lower-most position where it is in mesh with teeth 35 on a rotative carrier, designated as a whole by the reference numeral 36, the shanks of the screws will be received in the upright portions of the slots 33, thereby preventing a longitudinal displacement of the rack 34 relatively to the bracket arms 31 by which the rack is carried. If the thumb screws 32 be tightened at this time the rack will be constantly maintained in engagement with the teeth 35 of the rotative carrier so that the latter in its rotation will move in unison with the carriage during the travel thereof. If, however, the operator desires to disconnect the carriage entirely from the tabulator mechanism so as to render the latter ineffective, it is merely necessary to lift the rack until the longitudinally extending portions of the slots 33 are in register with the shanks of the screws 32 and then effect a slight longitudinal movement of the rack in order that the shanks of the screws may be seated within such longitudinal portions of the slots. The effect of this adjustment of the rack is to disengage the rack from the teeth on the carrier and maintain the rack elevated above and clear of the teeth 35 on the carrier. By tightening the screws 32 the rack may be retained indefinitely in this position.

The carrier 36 is in the nature of a wheel or rotative member provided, as hereinbefore explained, with teeth 35 on the periphery thereof. This wheel rotates on a spindle 37 which forms part of a bracket 38 designated as a whole by the reference numeral 38. The bracket 38 may be detachably secured to the frame of the machine at the front portion thereof by headed screws 39, which pass through openings 39^a in a foot piece in the bracket and engage in tapped openings in the cross bar 40 of the frame of the machine. It will be seen that the rotative stop carrier or wheel 36 is supported in an upright position at the front of the machine and centrally thereof. It will be understood from an inspection of Fig. 4 that the axis of the wheel is in a vertical plane which extends fore and aft of the machine and cuts the printing point 130

and printing point indicator 28. The wheel or stop carrier is slotted radially throughout near the periphery thereof, as at 41 (Fig. 4) for the reception of a series of 5 circularly arranged column stops 42, each of which may be constructed as best shown in Figs. 6 and 7. Each stop is preferably made of sheet metal and is slotted at 43 to provide a spring bearing portion 44. This 10 arm is provided at its free end with a nib or enlargement 45 which prevents an accidental displacement of the stop from the slot in which it is received when the stop is projected to the operative position, as shown 15 in Fig. 7. The opposite end of the stop is likewise provided with a lug or projection 46 which limits the longitudinal movement of the stop in the opposite direction, as indicated in Fig. 6. The lug 46 and nib 45 20 thus co-act with the body portion of the wheel or stop carrier to limit the stop in its movement fore and aft of the machine, or into and out of operative position. The spring arm or portion 44, which is formed integral 25 with its stop, constitutes a spring bearing member which enables a stop to be sprung into place within its slot or to be removed therefrom. Thus by depressing the nib 45 toward the body portion of the stop until the 30 nib clears the associated wall of the opening, the stop may be withdrawn from the slot and detached from the carrier. Fig. 4 shows the parts as they appear with some of the stops removed. In a like manner a stop 35 may be introduced into place by pressing the arm 44 against the body portion of the stop and introducing the stop into an opening in the carrier until the nib 45 passes to the rear face of the carrier where it will spring 40 back to normal position, preventing an accidental withdrawal of the stop. Moreover, the effect of this integral portion of the spring stop is to produce sufficient friction between the stop and the end walls of a 45 slot to hold the stop indefinitely in the operative or inoperative position to which it may be moved on the carrier. In the present instance I have shown one hundred and twenty stop openings arranged in a circle 50 in the stop carrier, and each opening is adapted to receive a stop 42 which may be moved on the carrier forwardly to the operative position at the front of the wheel or carrier, as indicated in Figs. 5 and 7, or 55 rearwardly to the inoperative position at the back of the wheel, as indicated in Figs. 3 and 5.

Arranged within the circular series of column stops is a series of circularly arranged indices 47 inscribed on the front face of the stop carrier. There are as many of these indices as there are stop receiving openings 41 in the carrier and the indices are correspondingly located. These 65 indices are adapted to be brought success-

sively into register with a pointer 48 fixed by a screw 49 to a sleeve 50 which is mounted on the forward end of the bearing portion or spindle 37 on which the wheel turns, and by which sleeve the wheel or stop carrier is held in position on the spindle. It 70 will be understood that a traveling movement of the carriage is effective to turn the stop carrier and to bring the indices 47 thereon successively into register with the 75 fixed pointer 48. The spacing of the indices 47 corresponds to that on the ordinary carriage scale and such indices 47 will accurately register the position of the carriage at any point in the travel thereof, as 80 will be readily understood from an inspection of Fig. 4 where each pointer 28 and 48 points to an index mark that indicates the same position of the carriage.

I have provided co-operative key controlled tabulator mechanism to co-act with the column stops which are in the operative position. In the present instance this co-acting key controlled tabulator mechanism comprises a series of denominational stops 85 51 which are in the nature of depending arms on angular levers 52. The forwardly projecting arm 53 of each of these levers carries a key 54 which is bent laterally, as indicated in Fig. 5. By the fanning arrangement of the lever arms 53 I am enabled to provide sufficient room for the denominational keys 54 in a single row across the machine and above the keyboard and yet arrange the stop bearing portions or arms 100 51 of the levers in a comparatively small widthwise space, as will be seen upon reference to Figs. 4 and 5. The various levers 52 are pivoted on a pivot rod 55 received and supported at its ends only in bearings 56 105 and secured therein by set screws 57. Those portions of the levers 52 which are apertured to receive the pivot rod 55 co-operate with spacing washers 58 supported on the pivot rod 55 and by which the levers 52 are 110 maintained spaced apart and are guided. Each bearing 56 is formed as a part of an arm 58 which extends forwardly and inwardly from the bracket 38, the arms 58 preferably being formed integral with the 115 bracket 38. From an inspection of Fig. 4 it will be seen that the denominational stops 51 are arranged at letter space distances apart, corresponding to the spacing of the column stops on the stop carrier, and that 120 there are eight of these denominational stops, each controlled by a separate key 54, and that these keys, reading from left to right, as indicated in Fig. 5, are inscribed with indices "M", "100T", "10T", "T", 125 "100", "10", "1", ". It will be noted that this reading of the indices on the denominational keys is in the natural order in which the reading of numerals inscribed on the sheet occurs, and that there is less 130

confusion in the mind of the operator in actuating the denominational keys than is the case where the inscriptions on the keys are in the reverse order of that in which the numerals actually appear when written.

5 Each lever 52 is provided with a stop finger 59 which co-acts with a depending portion 60 on the collar 50 to arrest the denominational stop lever in its return movement to normal position. The return movement of each denomination stop lever is effected by a contractile spring 61 connected at one end to the lever, as at 62, and connected at its opposite end with the depending portion 60 of the collar 50. The rear end of the spring may be connected to the collar by extending through an opening in the portion 60 thereof and having a hook 63 on the end of the spring to connect the spring with the member 60.

20 In order to effect a release of the carriage at the actuation of any of the denominational stops, I have provided a universal bar 64 which extends beneath the forwardly 25 projecting arms 53 of the levers 52. The ends of the universal bar are bent inwardly and rearwardly to provide two supporting arms 65 and 66 which are formed with bearing portions 67. The bearing portions of 30 the arms 65 are apertured to receive the pivot rod 55 so that the universal bar, as well as the stop levers 52, are pivoted on the pivot rod 55. The left-hand supporting arm 66 of the universal bar is provided with 35 an upwardly extending arm 68 arranged in the rear of a universal bail 69, supported by depending arms 70 on the carriage. The arms 70 are pivoted as at 71 to ears formed on the brackets 31. One of the arms 70 is 40 provided with a rearwardly extending arm 72 which is received in a slot 73 formed in the release lever 24. In the No. 10 Remington machine there are two release levers 24 provided and, if desired, each of the arms 45 70 may be provided with a rearwardly extending arm 72 for connection with the associated release lever 24 in the manner indicated.

50 From the foregoing description it will be understood that a depression of a denominational key is effective to turn the associated stop lever 52 to the position indicated in Fig. 8, thereby bringing the associated denominational stop 51 into the path of those 55 column stops which have been moved forwardly to the operative position, and at the same time the release arm 68 will be moved forwardly to effect a forward movement of the bail 69, thereby actuating the release 60 lever or levers 24 to lift the feed rack and free the carriage from control of the escapement mechanism. When pressure on the depressed denominational key is released, the parts will be returned to normal position 65 after the carriage has been arrested in the

denominational position determined by the particular denomination key which has been depressed.

The means by which the column stops are "set" or moved to operative position will now be described. Extending centrally through a bearing opening in the fixed spindle 37 on which the stop carrier rotates, is a key stem 74 arranged to slide fore and aft of the machine in its bearing opening. The forward end of this key stem is provided with a finger key 75 by which the stop setting device may be actuated. A coiled expansion spring 76 surrounds the stem 74 and bears at one end against the finger key 75 and at its opposite end against the forward end of the spindle 37, the power of this spring being exerted to normally maintain the key 75 in the forward position represented in Fig. 3. The rear end of the stem 74 is slotted, as at 77, to receive the upper end of a stop setting device 78 which is pivoted at 78a to the stem. The stop setting device is in the nature of a lever of the first order pivoted at 79 on rearwardly extending ears 80 that project from the bracket 38. The body portion of the bracket is slotted at 81 to receive the stop setting device or lever 78 and enable the lower end thereof to be projected forwardly beyond the front face of the bracket 38 to the operative position represented in Fig. 7. The width of the engaging portion 82 of the stop setting device is such that it can coact with but one column stop 42 at a time to move the column stops forward from the position represented in Fig. 3 to that shown in Fig. 7. The effect of this movement of a column stop is to bring it from a position from the rear side of the stop carrier where the stop is in the inoperative position, to a position at the forward side of the stop carrier where the stop is in the operative position. It will be understood that a rotative movement of the stop carrier is effected by an intermittent letter feed movement of the carriage in the direction of its feed in order to bring the column stops successively in register with the engaging end 82 of the stop setting device, so that the latter when actuated may engage the registering stop and move it to operative position. The stop setting device is therefore operative individually successively and selectively to move the column stops to operative position. They are moved selectively into operation in the sense that any desired column stop may be moved to operative position as determined by the position of the carriage in its line of travel.

The means for clearing the stops or returning them to normal inoperative position consists in the present instance of a clearing device designated as a whole by the reference 83. This device includes a hub portion 83a pivoted on the pivot rod 55 and

having a depending arm 84 provided with a finger piece 85 by which the clearing device may be turned on its pivot from the normal position shown in Fig. 3 to the operative position represented in Fig. 6. The clearing device is provided with a laterally projecting arm 86 having an inclined face 87 which constitutes a cam or wiper which is coöperative with the column stops to cam them rearwardly from the operative to the inoperative position, as represented in Fig. 6. It will be understood that the column stops are brought successively into coöperation with the wiper to cam them to inoperative position during the travel of the carriage from right to left. The lower end of the clearing device 83 is provided with an engaging device or pawl 88 pivoted thereto by a shouldered pivot screw 89. The pawl 88 is provided with a shouldered portion 90 (Figs. 4 and 6) adapted to contact with the body portion of the clearing device to limit the rotative movement of the pawl 88 on its pivot 89 in one direction. A leaf spring 91 is secured at one end, as indicated at 92 in Fig. 3, to the body portion of the clearing device and bears at its free end portion against the pawl 88 to hold it normally in the position represented in Fig. 4 with the engaging portion 90, limiting the movement of the pawl around its pivot 89.

A coöperating engaging member designated as a whole by the reference numeral 92 is mounted to slide vertically in a housing 93 secured by a screw 94 to the bracket 38. The upper end portion of this member 92 is provided with an engaging nose 95 which is beveled at 96 and is adapted to co-operate with the pawl 88 when the clearing device is moved rearwardly to the operative position, as shown in Fig. 6. The engaging member 92 is also provided with a forwardly extending finger piece 97 which extends through a slot 98 in the housing 93. The engaging member has a depending spindle 99 which extends through an opening in the bottom of the housing and a nut 100 is threaded on the lower end of the spindle. An expansion spring 101 surrounds the spindle 99 and bears at its lower end against the bottom wall of the housing and at its upper end against the body portion of the engaging device 92. The power of this spring is therefore exerted to normally maintain the engaging member 92 in the elevated position with the nut 100 bearing against the bottom of the housing in which the engaging member is received and adapted to move. It will be understood that a rearward movement of the clearing device 83 is effective to bring the lower end of the pawl 88 into contact with the inclined face 96 of the engaging member 92 and to depress said engaging member 65 until the pawl has passed behind the engag-

ing nose 95 on the member 92. Then the latter is elevated by its spring 101 to bring the engaging nose 95 forward of the pawl 88 and thereby automatically lock the clearing device against return movement. This locking engagement, however, may be released at any time by a depression of the finger piece 97 and when thus released the clearing device will be returned to normal position shown in Fig. 3, by a leaf spring 102. This spring is fixed at one end to the clearing device by a screw 103 and bears at its free end against a pin 104, which projects inwardly from the left-hand bracket arm 58.

I have provided automatically operating means for releasing the carriage from control of the escapement mechanism when the clearing device is operated so that the carriage traveling under the influence of its driving spring may wipe out or clear the column stops which are in the operative position. Thus from an inspection of Fig. 5 it will be seen that the hub 83^a of the clearing device is reduced at one end, as at 105, and has seated thereon and fixedly connected therewith a forwardly projecting arm 106. This arm is bent to the left from the hub 83^a and then extends forwardly to overlap the universal bar 64 by an actuation of which the carriage is released. It will be seen, therefore, that a rearward movement of the clearing device to the operative position shown in Fig. 6 is effective to turn the arm 106 downwardly, thereby depressing the universal bar 64 and moving the upwardly extending arm 68 connected therewith forwardly, as represented in Fig. 6, to effect a forward movement of the universal bar 69 and thus release the carriage. If the carriage be at the extreme right when the clearing device 83 is moved to and locked in the operative position shown in Fig. 6, a simultaneous release of the carriage is effected and a revolution of the stop carrier is effected, bringing all the column stops successively into engagement with the cam or wiper 87, to clear all of the column stops or move them rearwardly on the carrier to the inoperative position.

In order to automatically release the clearing device from its locked position, I have provided a releasing device which is fixed on the stop carrier 36. This device comprises an angular bracket 107 having a forwardly engaging portion 108, the bracket being detachably secured by screws 109 or other suitable means to the forward face of the rotative stop carrier 36 near the periphery thereof. From an inspection of Figs. 3 and 6 it will be understood that the engaging portion 108 of the releasing device has a rotative path of movement which is intersected by the pawl 88 when the clearing device is locked in the operative posi-

130

tion by said pawl. The position of the releasing bracket 107 on the stop carrier is such that it is not brought into coöperation with the pawl 88 until all of the column stops have been cleared by the wiper 87 as will hereinafter more clearly appear. When, however, the stops have been cleared by the wiper, the releasing device will be brought into engagement with the pawl 88 before the carriage has completed its movement and the effect of this engagement between the device 107 and the pawl 88 is to turn the latter on its pivot 89 to the right against the power of the spring 91. The pivotal movement of the pawl to the right in the manner described is effective to withdraw the pawl from engagement with the spring pressed engaging member 92 so as to enable the clearing device 83 to be returned to normal position by its spring 102. In order to limit the movement of the clearing device 83 and the arm 106 carried thereby, I have provided a pin 110 fixed in the left-hand bearing portion 56 of the supporting bracket, this pin projecting into a slot 111 formed in the bearing portion of the arm 106. The pin and slot 110-111 is thus effective to limit the return movement of the clearing device 83 and to normally maintain the arm 106 in a position above the universal bar 64, as shown in Fig. 3, where there may be sufficient lost motion between the arm 106 and the universal bar to enable the wiper to be brought substantially into operative position before the carriage is released.

While I prefer to employ as many, or substantially as many, column stops as there are letter space positions of the carriage in the travel thereof, it should be understood that this is not necessary in all instances as it may be found sufficient to provide a series of column stops grouped at letter space intervals and corresponding in number to only a portion of the travel of the carriage. Moreover it will be understood that the construction is such that the rotative column stop carrier, column stops, stop setting device and stop clearing device may be employed in connection with carriages of different lengths. Thus, I have shown a construction in the present instance in which provision is made for the use of as many as one hundred and twenty column stops arranged at letter space intervals. This enables the mechanism to be used in connection with carriages of different lengths up to one hundred and twenty letter spaces. For example, if a carriage in which provision is made for a feed of but seventy letter spaces is provided, then only a corresponding number of column stops on the stop carrier need be employed. However, the operations will remain the same as for a carriage of greater length and no change in the construction of

the features mentioned is required, except that an adjustment of the releasing device 107 may be required.

Carriages are generally made in standard lengths, such, we will say for example, as to provide for seventy-five, ninety-five, and one hundred and twenty letter spaces. It may be assumed that in the present case a carriage of a length to provide for seventy-five letter spaces is employed. It will be observed that the releasing device 107 is so positioned that it will not release the pawl 88 until say the first seventy stops have been cleared, assuming that a full complement of say seventy stops are employed. For longer carriages the releasing device 107 will be set correspondingly on the carrier 36 as shown in Fig. 4 by the positions of the screw holes 112 in the carrier. I prefer, however, to employ a releasing device such as is shown in Fig. 3^a and in which the releasing device as a whole is designated by the reference numeral 113 and comprises a contact portion 114, corresponding to the part 108 in the previously described construction, for coöperation with the pawl 88. The contact portion 114 is formed as a part of a carrying member 115 which resembles the column stops except that there is no movement of the releasing device 113 fore and aft of the machine in the slot 41 of the carrier. The spring finger 116 with its enlargement, however, enables me to adjust the releasing device to any opening 41 around the wheel 36 by springing the supporting portion of the device into place. It will be understood that with this device it may be adjusted to any letter space interval provided by the series of circularly arranged openings 41.

I have referred in the accompanying claims to a constantly maintained operative connection between the carriage and the rotative carrier for the column stops. It should be understood that by this and like expressions I mean to include a construction like that shown, for example, in which whenever the tabulating mechanism is in condition for use, or is effective or operative for the purposes for which it was devised, there is a constantly maintained operative connection between the carriage and stop carrier; although the carriage and carrier may be disconnected by means, such for example as are shown in Fig. 2, when the use of the tabulator is to be dispensed with indefinitely.

It will be observed that the rotative carrier when connected to the carriage always has a definite predetermined relation to the carriage at any given letter space position of the latter, so that a column stop once set at "60" for example on the carrier will always arrest the carriage at "60" on the carriage scale by the coöperation of said stop with the decimal stop. While this

definite relation is not maintained when the rack 34 is thrown out of mesh with the carrier, nevertheless the relation may be quickly reestablished by moving the carriage to a letter space position on the carriage scale corresponding to that of the rotative carrier, as the position of the latter is indicated by the pointer 48 and the indices 47, before throwing the rack 34 back into mesh with the teeth 35.

Various changes may be made without departing from my invention and certain features may be employed without others.

What I claim as new and desire to secure by Letters Patent, is:—

1. In a typewriting machine and tabulating mechanism, the combination of a carriage, a rotative column stop carrier, a constantly maintained operative connection between the carriage and said rotative carrier to cause the latter to rotate during the travel of the carriage, a series of column stops carried by the carrier and mounted for individual movement thereon into operative position, a coöperative tabulator stop, and a key controlled stop set device operative individually on the column stops to move them separately into operative position.

2. In a typewriting machine and tabulating mechanism, the combination of a carriage, a rotative column stop carrier, a constantly maintained operative connection between the carriage and said rotative carrier to cause the latter to rotate during the travel of the carriage, a series of column stops carried by the carrier and mounted for individual movement thereon into operative position, a coöperative tabulator stop, a key controlled stop set device operative individually on the column stops to move them separately into operative position, and means for moving said column stops into inoperative position.

3. In a typewriting machine and tabulating mechanism, the combination of a carriage, a rotative column stop carrier, a constantly maintained operative connection between the carriage and said rotative carrier to cause the latter to rotate during the travel of the carriage, a series of column stops carried by the carrier and mounted for individual movement thereon into operative position, a coöperative tabulator stop, a key controlled stop set device operative individually on the column stops to move them separately into operative position, and key controlled means operative successively on said column stops to move them to inoperative position.

4. In a typewriting machine and tabulating mechanism, the combination of a carriage, a rotative column stop carrier, a constantly maintained operative connection between the carriage and said rotative carrier to cause the latter to rotate during the travel

of the carriage, a series of column stops carried by the carrier and mounted for movement thereon into and out of operative position and adapted to remain indefinitely in either of such positions, a coöperative tabulator stop, a key controlled stop set device operative on the column stops to move them into operative position, a wiper coöperative with said column stops to move them to inoperative position, and a key for controlling the movement of said wiper into and out of coöperative relation with said column stops.

5. In a typewriting machine and tabulating mechanism, the combination of a carriage, a rotative column stop carrier, a constantly maintained operative connection between the carriage and said rotative carrier to cause the latter to rotate during the travel of the carriage, a series of column stops carried by the carrier and mounted for individual movement thereon into and out of operative position and adapted to remain indefinitely in either of such positions, a coöperative tabulator stop, and a key controlled stop set device operative individually on the column stops to move them separately into operative position, the column stops being arranged a letter space distance apart and brought successively into register with said stop set device during the travel of the carriage.

6. In a typewriting machine and tabulating mechanism, the combination of a carriage, a rotative column stop carrier, a constantly maintained operative connection between the carriage and said rotative carrier to cause the latter to rotate during the travel of the carriage, a series of column stops carried by the carrier and mounted for individual movement thereon into and out of operative position and adapted to remain indefinitely in either of such positions, a coöperative tabulator stop, a key controlled stop set device operative individually on the column stops to move them separately into operative position, the column stops being arranged a letter space distance apart and brought successively into register with said stop set device during the travel of the carriage, a wiper coöperative with the column stops to move them successively to inoperative position during a rotative movement of said carrier, and a key for controlling the movement of said wiper into and out of coöperative relation with said column stops.

7. In a typewriting machine and tabulating mechanism, the combination of a carriage, a rotative column stop carrier, an operative connection between the carriage and said rotative carrier to cause the latter to rotate during the travel of the carriage, a series of column stops carried by the carrier and mounted for individual movement thereon into and out of operative position and adapted to remain indefinitely in either of

such positions, a coöperative tabulator stop, a key controlled stop set device operative individually on the column stops to move them separately into operative position, the 5 column stops being arranged a letter space distance apart and brought successively into register with said stop set device during the travel of the carriage, a wiper coöperative with the column stops to move them success- 10 sively to inoperative position during a rotative movement of said carrier, a key for controlling the movement of said wiper into and out of coöperative relation with said column stops, and carriage releasing means controlled by the wiper key.

8. In a typewriting machine and tabulating mechanism, the combination of a carriage, a rotative column stop carrier, an operative connection between the carriage and 20 said rotative carrier to cause the latter to rotate during the travel of the carriage, a series of column stops carried by the carrier and mounted for movement thereon into and out of operative position, a wiper coöperative 25 with the column stops to move them successively to inoperative position during a rotative movement of said carrier, a key for controlling the movement of said wiper into and out of coöperative relation with 30 said column stops, and carriage releasing means controlled by the wiper key.

9. In a typewriting machine and tabulating mechanism, the combination of a carriage, a support detachably fixed to the 35 frame of the machine, a stop carrier carried by and movable on said support, a series of column stops carried by said carrier and movable thereon into and out of operative position, means for moving said carrier in 40 unison with the carriage, and means carried by said support for moving the column stops selectively into operative position.

10. In a typewriting machine and tabulating mechanism, the combination of a carriage, a support detachably fixed to the 45 frame of the machine, a stop carrier carried by and movable on said support, a series of column stops carried by said carrier and movable thereon into and out of operative 50 position, means for moving said carrier in unison with the carriage, means carried by said support for moving the column stops selectively into operative position, and means carried by said support for moving the column stops to an inoperative position.

11. In a typewriting machine and tabulating mechanism, the combination of a carriage, a support detachably fixed to the machine, a stop carrier carried by and movable 60 on said support, a series of column stops carried by said carrier and movable thereon into and out of operative position, means for moving said carrier in unison with the carriage, means carried by said support for moving the column stops se- 65

lectively into operative position, and a key controlled coöperative tabulator stop carried by said support.

12. In a typewriting machine and tabulating mechanism, the combination of a carriage, a support detachably fixed to the machine, a stop carrier carried by and movable on said support, a series of column stops carried by said carrier and movable thereon into and out of operative position, means for moving said carrier in unison with the carriage, stop setting means for moving the stops into operative position, clearing means for moving the stops into operative position, a key controlled coöperative tabulator stop, and a carriage releasing device, said stop setting means, clearing means, coöperative tabulator stop and carriage releasing device all being carried by said support.

13. In a typewriting machine and tabulating mechanism, the combination of a carriage, a support detachably fixed to the machine, a stop carrier carried by and movable on said support, a series of column stops carried by said carrier and movable thereon into and out of operative position, means for moving said carrier in unison with the carriage, means carried by said support for moving the column stops selectively into operative position, and a series of key controlled denominational stops carried by said support.

14. In a typewriting machine and tabulating mechanism, the combination of a carriage, a support detachably fixed to the frame of the machine, a stop carrier carried by and movable on said support, a series of column stops carried by said carrier and movable thereon into and out of operative position, said column stops being arranged at letter space intervals, means for moving said carrier in unison with the carriage, and means for moving the column stops selectively into operative position.

15. In a typewriting machine and tabulating mechanism, the combination of a carriage, a support detachably fixed to the frame of the machine, a stop carrier carried by and movable on said support, a series of column stops carried by said carrier and movable thereon into and out of operative position, said column stops being arranged at letter space intervals, means for moving said carrier in unison with the carriage, and a key actuated stop setting device coöperative individually with the column stops to move them into operative position, the stop setting device being carried by said support and the column stops being brought successively into coöperative relation with said stop setting device during the movement of the carrier concurrently with the carriage.

16. In a typewriting machine and tabulating mechanism, the combination of a carriage, a support fixed to the machine, a ro-

5 tative carrier carried by said support and adapted to turn thereon, means for maintaining a constant operative connection between the carriage and said carrier to move the latter in unison with the carriage, a series of column stops carried by the carrier and movable thereon into and out of operative position, and a key controlled stop setting device carried by said carrier and operative individually on the column stops to move them into operative position, the column stops being moved successively into operative relation with said stop setting device during the rotative movement of said 10 carrier effected during the travel of the carriage.

15 17. In a typewriting machine and tabulating mechanism, the combination of a carriage, a support fixed to the machine, a rotative carrier carried by said support and adapted to turn thereon, said carrier being arranged upright at the front of the machine, means for operatively connecting said carrier to move in unison with the carriage, a series of stops carried by said carrier and movable thereon into and out of operative position, and key controlled stop setting means operable at will for moving said stops selectively into operative position.

20 18. In a typewriting machine and tabulating mechanism, the combination of a carriage, a rotative stop carrier arranged in an upright position at the front of the machine, means for operatively connecting the 25 said carrier to the carriage to move in unison therewith during the travel of the carriage, a series of column stops carried by said carrier, a series of angular levers pivoted in front of the said carrier, one set of 30 the arms of said levers being formed as denomination stops which are movable into and out of the path of said column stops and the other set of arms of said levers carrying denominational keys, and a carriage 35 releasing device controlled by said levers.

40 19. In a typewriting machine and tabulating mechanism, the combination of a carriage, a support fixed to the machine, a rotative carrier carried by said support and adapted to turn thereon, said carrier being arranged upright at the front of the machine, means for operatively connecting said carrier to move in unison with the carriage, a series of column stops carried by said carrier and movable thereon into and out of operative position, key controlled stop setting means for moving the column stops selectively into operative position, and a series of key controlled cooperative denominational stops.

45 20. In a typewriting machine and tabulating mechanism, the combination of a carriage, a support detachably fixed to the frame of the machine, a rotative carrier carried by said support and adapted to turn

thereon, said carrier being arranged upright at the front of the machine, means for operatively connecting said carrier to move in unison with the carriage, a series of column stops carried by said carrier and movable thereon into and out of operative position, key controlled stop setting means for moving the column stops selectively into operative position, a series of key controlled cooperative denominational stops, and a carriage releasing device controlled by an actuation of any of said denominational stops, the stop setting means, denominational stops and carriage releasing device as well as the column stop carrier being mounted on and detachable with said support.

50 21. In a typewriting machine and tabulating mechanism, the combination of a carriage, a support fixed to the machine, a rotative carrier carried by said support and adapted to turn thereon, said carrier being arranged upright at the front of the machine, means for operatively connecting said carrier to move in unison with the carriage, a series of column stops carried by said carrier and movable thereon into and out of operative position, key controlled stop setting means for moving the column stops selectively into operative position, a key controlled cooperative tabulator stop, a series of letter space indices on said stop carrier, and an indicator cooperating with said indices.

55 22. In a typewriting machine and tabulating mechanism, the combination of a carriage, a rotative stop carrier arranged in an upright position at the front of the machine, means for operatively connecting the said carrier to the carriage to move in unison therewith during the travel of the carriage, a series of column stops carried by said carrier and movable thereon into and out of operative position, key controlled stop setting means for moving said column stops selectively into operative position, a series of denominational stop carrying levers arranged at the front of the machine and each provided with a key situated above the keyboard, and a carriage releasing device controlled by said levers.

60 23. In a typewriting machine and tabulating mechanism, the combination of a carriage, a rotative stop carrier arranged in an upright position at the front of the machine, means for operatively connecting the said carrier to the carriage to move in unison therewith during the travel of the carriage, a series of column stops carried by said carrier and movable thereon into and out of operative position, key controlled stop setting means for moving said column stops selectively into operative position, a series of denominational stop carrying levers arranged at the front of the machine and each provided with a key situated above

the keyboard, a carriage releasing device controlled by said levers, and a support detachably fixed to the frame of the machine and on which said stop carrier, stop setting means, stop carrying levers and carriage releasing device are mounted.

24. In a typewriting machine and tabulating mechanism, the combination of a carriage, a rotative stop carrier arranged in an upright position at the front of the machine, means for operatively connecting the said carrier to the carriage to move in unison therewith during the travel of the carriage, a series of column stops carried by said carrier and movable thereon into and out of operative position, key controlled stop setting means for moving said column stops selectively into operative position, a series of angular levers pivoted in front of said carrier, one set of the arms of said levers being formed as denomination stops which are movable into and out of the path of said column stops and the other set of the arms of said levers carrying denominational keys, and a carriage releasing device controlled by said levers.

25. In a typewriting machine and tabulating mechanism, the combination of a carriage, a rotative stop carrier arranged in an upright position at the front of the machine, means for operatively connecting the said carrier to the carriage to move in unison therewith during the travel of the carriage, a series of column stops carried by said carrier and movable thereon into and out of operative position, key controlled stop setting means for moving said column stops selectively into operative position, a series of angular levers pivoted in front of said carrier, one set of the arms of said levers being formed as denomination stops which are movable into and out of the path of said column stops and the other set of the arms of said levers carrying denominational keys, a carriage releasing device controlled by said levers, and a support detachably fixed to the frame of the machine and on which said stop carrier, stop setting device, angular levers and carriage releasing device are mounted.

26. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled co-operative tabulator stop, and key controlled stop setting means operable at will for moving the column stops into operative position.

27. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon to one side or the other of said carrier into and out of operative position and which are adapted to remain indefinitely in either of said positions, a key controlled co-operative tabulator stop, key controlled stop setting means arranged at one side of said rotative carrier and operative at will to move the column stops into operative position, and means arranged at the other side of said rotative carrier for moving the column stops out of operative position.

28. In a typewriting machine and tabulating mechanism, the combination of a carriage, a rotative stop carrier carried by the front of the machine, an operative connection between the carriage and said carrier for effecting a rotative movement of the carrier in unison with the carriage during the travel of the latter, a series of circularly arranged column stops carried by said carrier and movable thereon to one side or the other of said carrier into and out of operative position and which are adapted to remain indefinitely in either of said positions, a key controlled co-operative tabulator stop, and key controlled stop setting means operative individually on the column stops to move them separately to operative position, the movement of the carriage carrying the column stops successively into register with said stop setting means.

29. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon to one side or the other of said carrier into and out of operative position and which are adapted to remain indefinitely in either of said positions, and a key controlled clearing device for moving the column stops out of operative position.

30. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are

adapted to remain indefinitely in either of said positions, and a key controlled wiper movable at will into and out of coöperative relation with the column stops and operative to move the column stops successively out of operative position during the travel of the carriage.

31. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled coöperative tabulator stop, key controlled stop setting means operative individually on the column stops to move them separately to operative position, the movement of the carriage carrying the column stops successively into register with said stop setting means, and a key controlled wiper movable at will into and out of coöperative relation with the column stops and operative to move the column stops successively out of operative position during the travel of the carriage.

32. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled clearing device for moving the column stops out of operative position, and locking means for locking said key controlled device in the operative position.

33. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, and automatically operating means for locking said wiper in coöperative relation with the column stops.

34. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, automatically operating means for locking said wiper in coöperative relation with the column stops, and automatically operating means for releasing said locking means.

35. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, automatically operating means for locking said wiper in coöperative relation with the column stops, and means operating automatically when all of the column stops have been moved out of the operative position to release said locking means and allow the wiper to be moved out of coöperative relation with the column stops.

36. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled clearing device for moving the column stops out of operative position, and means for releasing the carriage when said clearing device is moved into coöperative relation with the column stops.

37. In a typewriting machine and tabulating mechanism, the combination of a carriage, a rotative stop carrier, an operative connection between the carriage and said

- carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, and means for releasing the carriage when said wiper is moved into coöperative relation with the column stops.
38. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, means for releasing the carriage when said wiper is moved into coöperative relation with the column stops, and means for locking the wiper in coöperative relation with the column stops.
39. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, means for releasing the carriage when said wiper is moved into coöperative relation with the column stops, means for locking the wiper in coöperative relation with the column stops, and automatically operating means for releasing said locking means.
40. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled clearing device for moving the column stops out of operative position, a spring pressed latch which locks the clearing device in its operative position, and automatically operative means for releasing said latch.

ing the travel of the latter, a series of circularly arranged column stops carried by said carrier and movable thereon into and out of operative position and which are adapted to remain indefinitely in either of said positions, a key controlled clearing device for moving the column stops out of operative position, locking means for locking said key controlled device in the operative position, and means carried by said rotative stop carrier and operative on said locking means to release the same.

41. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, automatically operating means for locking said wiper in coöperative relation with the column stops, and a device carried by said rotative stop carrier and coöperative with said locking means at a given point in the rotation of said carrier to release the locking means and enable the wiper to return to normal position out of coöperative relation with the column stops.

42. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon to one side or the other of said carrier into and out of operative position and which are adapted to remain indefinitely in either of said positions, a key controlled clearing device for moving the column stops out of operative position, a spring pressed latch which locks the clearing device in its operative position, and automatically operative means for releasing said latch.

43. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to

- remain indefinitely in either of said positions, a key controlled wiper movable at will into and out of coöperative relation with the column stops and operative to move the column stops successively out of operative position during the travel of the carriage, a spring pressed latch for locking the wiper in coöperative relation with said column stops, and automatically operating means for releasing said latch. 10
44. In a typewriting machine and tabulating mechanism, the combination of a carriage, a rotative stop carrier, an operative connection between the carriage and said carrier for effecting a rotative movement of the carrier in unison with the carriage during the travel of the latter, a series of circularly arranged column stops carried by said carrier and movable thereon into and out of operative position and which are adapted to remain indefinitely in either of said positions, a key controlled wiper movable at will into and out of coöperative relation with the column stops and operative to move the column stops successively out of operative position during the travel of the carriage, a pivoted spring pressed latch for locking the wiper in coöperative relation with said column stops, and a device carried by said rotative carrier and coöperative with said latch at a given point in the rotation of the carrier to turn said latch on its pivot and thus release the latch and enable the wiper to return to normal position out of coöperative relation with said column stops. 20
45. In a typewriting machine and tabulating mechanism, the combination of a carriage, a stop carrier, a series of column stops movable into and out of operative position on the stop carrier, clearing means for moving the column stops out of operative position during the travel of the carriage, and automatically operating means independent of the column stops for locking the clearing means in coöperative relation with said column stops. 30
46. In a typewriting machine and tabulating mechanism, the combination of a carriage, a stop carrier, a series of column stops movable into and out of operative position on the stop carrier, a wiper movable into and out of coöperative relation with the column stops and operative thereon during the travel of the carriage to move the column stops out of operative position, and automatically operating means independent of the column stops for locking said wiper in coöperative relation with said stops. 50
47. In a typewriting machine and tabulating mechanism, the combination of a carriage, a stop carrier, column stops carried by said carrier and movable thereon into and out of operative position, a clearing device coöperative with said column stops to move them out of operative position, means for locking said clearing device in coöperative relation with said stops, and an automatically actuated releasing device coöperative with a part of said locking means to move it to releasing position and free the clearing device. 70
48. In a typewriting machine and tabulating mechanism, the combination of a carriage, a stop carrier, column stops carried by said carrier and movable thereon into and out of operative position, a clearing device coöperative with said column stops to move them out of operative position, means for locking said clearing device in coöperative relation with said stops, and an automatically actuated releasing device carried by said stop carrier and moved thereby into engagement with a part of said locking means and release it from locking engagement and free the clearing device. 75
49. In a typewriting machine and tabulating mechanism, the combination of a carriage, a series of column stops movable into and out of operative position and adapted to remain indefinitely in either of said positions, a clearing device movable into and out of coöperative relation with the column stops and operative to move the column stops out of operative position, means for locking said clearing device in coöperative relation with the column stops, and an adjustable releasing device operative at a predetermined point in the travel of the carriage on a part of said locking means to shift it to the releasing position to free the clearing device and enable the latter to move out of coöperative relation with said column stops. 90
50. In a typewriting machine and tabulating mechanism, the combination of a carriage, a series of column stops movable into and out of operative position and adapted to remain indefinitely in either of said positions, a clearing device movable into and out of coöperative relation with the column stops and operative to move the column stops out of operative position, means for locking said clearing device in coöperative relation with the column stops, and a releasing device which moves in unison with the carriage and which by the travel with the carriage is brought into contact with a part of said locking means to move it to the releasing position and thereby free the clearing device. 105
51. In a typewriting machine and tabulating mechanism, the combination of a carriage, a series of column stops movable into and out of operative position and adapted to remain indefinitely in either of said positions, a wiper movable into and out of coöperative relation with the column stops and operative during the travel of the carriage to move the column stops out of operative position, means for locking said wiper in co- 120
- 125
- 130

- operative relation with the column stops, and a releasing device independent of the column stops and operative at a predetermined point in the travel of the carriage on 5 said locking means to shift a part thereof to the releasing position to free the wiper and enable it to move out of coöperative relation with said column stops.
52. In a typewriting machine and tabulating mechanism, the combination of a carriage, a series of column stops movable into and out of operative position and adapted to remain indefinitely in either of said positions, a clearing device movable into and out 10 of coöperative relation with the column stops and operative to move the column stops out of operative position, means for locking said clearing device in coöperative relation with the column stops, and a releasing device which is movable in unison with the carriage and operative at a predetermined point in the travel of the carriage on 15 a part of said locking means to shift it along with the releasing device to the releasing 20 position to free the clearing device and enable the latter to move out of coöperative relation with said column stops, said column stops, clearing device, locking means, and releasing device being arranged at the front 25 of the machine.
53. In a typewriting machine and tabulating mechanism, the combination of a carriage, a series of column stops movable into and out of operative position and adapted 30 to remain indefinitely in either of said positions, a wiper movable into and out of coöperative relation with the column stops and operative during the travel of the carriage to move the column stops out of operative position, means for locking said wiper in coöperative relation with the column stops, and a releasing device which moves in unison with the carriage and which by the 35 travel with the carriage is brought into contact with a part of the locking means to move it to the releasing position and thereby free the wiper, said column stops, wiper, locking means, and releasing device being arranged at the front of the machine.
54. In a typewriting machine and tabulating mechanism, the combination of a carriage, a stop carrier, column stops carried by said carrier and movable thereon into and out of operative position, a clearing device 40 coöperative with said column stops to move them out of operative position, means for locking said clearing device in coöperative relation with said stops, said locking 45 means comprising a spring-pressed latch which is automatically engaged when the clearing device is moved to the operative position, and means operative at a predetermined point in the travel of the carriage 50 for shifting said latch against the pressure

of its spring to releasing position in order 65 to free the clearing device.

55. In a typewriting machine and tabulating mechanism, the combination of a carriage; a rotative stop carrier operatively connected to the carriage to move in unison therewith; column stops carried by and movable on said stop carrier into and out of operative position; and stop set mechanism coöperative with said column stops to move them into operative position, said stop 70 set mechanism comprising a stop set device at one side of the carrier and a controlling key at the other, and an intermediate actuating member between said key and device, said member passing axially through said 75 carrier.

56. In a typewriting machine and tabulating mechanism, the combination of a carriage; a rotative stop carrier operatively connected to the carriage to move in unison therewith; column stops carried by and movable on said stop carrier into and out of operative position; and stop set mechanism coöperative with said column stops to move them into operative position, said stop 80 set mechanism comprising a stop set device at one side of the carrier and a controlling key at the other, and an intermediate actuating member between said key and device, said member passing axially through said 85 carrier.

57. In a typewriting machine and tabulating mechanism, the combination of a carriage; a rotative stop carrier operatively connected to the carriage to move in unison therewith; column stops carried by and movable on said stop carrier into and out of operative position; and stop set mechanism coöperative with said column stops to move them into operative position, said stop 90 set mechanism comprising a stop set lever at one side of said stop carrier and a controlling key at the other, and a connecting rod between said key and lever and passing axially through the carrier.

58. In a typewriting machine, the combination of a slotted stop carrier, and a series of stops mounted in the slots for sliding movement into and out of operative position, each of said stops having an integral spring bearing portion by which the associated stop is held against accidental displacement from either of said positions to which it may be moved.

59. In a typewriting machine, the combination of a slotted stop carrier, and a stop 115 detachably mounted in a slot in said carrier and having a spring bearing portion and a retaining nib that normally prevents

5 a displacement of the stop from the slot but which nib may be sprung inwardly to clear the coöperative wall of the slot by reason of the spring bearing portion to enable a withdrawal of the stop from the slot to be effected.

10 60. In a typewriting machine, the combination of a stop carrier which has a slot extending therethrough, and a stop which extends through said slot and is movable therein to project the stop from one face or the other of the carrier, said stop having a spring bearing member that presses outwardly against a wall of the slot to hold the 15 stop against accidental displacement from either of the two said positions to which it may be moved.

20 61. In a typewriting machine, the combination of a stop carrier which has a slot extending therethrough, a stop which extends through said slot and is movable therein to project the stop from one face or the other of the carrier, said stop having a spring bearing member that presses outwardly 25 against a wall of the slot to hold the stop against accidental displacement from either of the two said positions to which it may be moved, and two projections at opposite ends of said stop to limit the movement thereof 30 in opposite directions.

35 62. In a typewriting machine, the combination of a stop carrier which has a slot extending therethrough, a stop which extends through said slot and is movable therein to project the stop from one face or the other of the carrier, said stop having a spring bearing member that presses outwardly against a wall of the slot to hold the stop against accidental displacement from 40 either of the two said positions to which it may be moved, and two projections at opposite ends of said stop to limit the movement thereof in opposite directions, one of said projections being carried by said spring bearing member and adapted to clear the coöperative wall of the slot by a deflection of the spring bearing member to enable the stop to be detached from the carrier.

45 63. In a typewriting machine and tabulating mechanism, the combination of a carriage, a series of column stops movable into and out of operative position and adapted to remain indefinitely in either of said positions, a coöperative key controlled tabulator 50 stop, a key controlled stop set device for moving the column stops individually and selectively into operative position, a key controlled clearing device movable into and out of coöperative relation with said column 55 stops and operative to move said column stops out of operative position, and automatically operating means for locking the clearing device in coöperative relation with the column stops, said column stops, coöperative stop, stop set device, clearing de-

vice, and locking means being arranged at the front of the machine.

64. In a typewriting machine and tabulating mechanism, the combination of a carriage, a series of column stops movable into and out of operative position and adapted to remain indefinitely in either of said positions, a coöperative key controlled tabulator stop, a key controlled stop set device for moving the column stops individually and selectively into operative position, and a key controlled wiper movable into and out of coöperative relation with said column stops and operative during the travel of the carriage to move said column stops out of operative position, said column stops, coöperative stop, stop set device, and wiper being arranged at the front of the machine. 70

65. In a typewriting machine and tabulating mechanism, the combination of a carriage, a series of column stops movable into and out of operative position and adapted to remain indefinitely in either of said positions, a coöperative key controlled tabulator stop, a key controlled stop set device for moving the column stops individually and selectively into operative position, and a key controlled wiper movable into and out of coöperative relation with said column stops and operative during the travel of the carriage to move said column stops out of operative position, said column stops, coöperative stop, stop set device, and wiper being arranged at the front of the machine and being detachable as a whole from the frame of the machine. 85

66. In a typewriting machine and tabulating mechanism, the combination of a carriage, a series of column stops movable into and out of operative position and adapted to remain indefinitely in either of said positions, a coöperative key controlled tabulator stop, a key controlled stop set device for moving the column stops individually and selectively into operative position, a key controlled wiper movable into and out of coöperative relation with said column stops and operative during the travel of the carriage to move said column stops out of operative position, and automatically operating means for locking the wiper in coöperative relation with the column stops, said column stops, coöperative stop, stop set device, wiper, and locking means being arranged at the front of the machine and being detachable as a whole therefrom. 100

67. In a typewriting machine, the combination of a carriage, a rotative member operatively connected to move in unison with the carriage during the travel thereof, said member having circularly arranged letter space indices thereon, a fixed spindle on which said rotative member turns, and a fixed pointer carried by said spindle and coöperative with said letter space indices. 115

68. In a typewriting machine and tabulating mechanism, the combination of a carriage, a rotative stop carrier, connecting means for causing the rotative carrier to move in unison with the carriage, and means for effecting and maintaining a disconnection of said connecting means so that the carriage may move independently of the carrier.
- 10 69. In a typewriting machine and tabulating mechanism, the combination of a carriage, a rotative stop carrier, geared connections between said carriage and carrier

to cause the carriage and carrier to move in unison, and means for separating and maintaining separated the geared connections to enable the carriage to travel indefinitely independently of the carrier.

Signed at the borough of Manhattan, city of New York, in the county of New York and State of New York this 30th day of August, A. D. 1912.

CHARLES E. SMITH.
